United States Patent Office

Des. 217,482
Patented May 5, 1970

217,482

FOOTBALL BLOCKING PRACTICE DEVICE OR SIMILAR ARTICLE

Richard H. Pray, 5731 Alondra, Goleta, Calif. 93107

Filed Nov. 25, 1968, Ser. No. 14,629

Term of patent 14 years

Int. Cl. D21—03

U.S. Cl. D34—5

FIG. 1

FIG. 2

FIG. 3

FIG. 1 is a three dimensional view of the device.

FIG. 2 is a front view of the device of FIG. 1 with the cross arms foreshortened to permit illustration on a larger scale than that of FIG. 1.

FIG. 3 is a side view of the device on FIG. 1 on the same scale as FIG. 2.

I claim:

The ornamental design for a football blocking practice device or similar article, as shown.
